[57] CLAIM

The ornamental design for a security restraint, as shown and described.

DESCRIPTION

FIG. 1 is a front elevational view of a security restraint showing my new design;

FIG. 2 is a rear elevational view thereof;

FIG. 3 is an enlarged left side elevational view thereof;

FIG. 4 is an enlarged right side elevational view thereof;

FIG. 5 is a top plan view thereof;

FIG. 6 is a bottom plan view thereof; and,

FIG. 7 is an inverted bottom, front, and right side perspective view thereof.

The vertical chain element in the views is understood to be of indeterminate length.

FIG. 3

FIG. 4

FIG. 5

FIG. 6

FIG. 7
